his Atty.

UNITED STATES PATENT OFFICE.

HARRY G. NORWOOD, OF BALTIMORE, MARYLAND, ASSIGNOR TO CONTINENTAL RAILWAY SUPPLY CORPORATION, OF NEW YORK, N. Y., A CORPORATION OF DELAWARE.

RAILWAY-RAIL ANCHOR.

Application filed September 29, 1927. Serial No. 222,764.

This invention relates to an improved one piece rail anchor or anticerper especially designed to be secured to the base portion of railway track rails and in engagement with 5 stationary parts of the road bed for the purpose of preventing longitudinal displacement of the rails during the travel of the rolling stock thereover.

The prime object of the invention is to 10 provide a simple, novel, durable, economical, practical and thoroughly efficient rail anchor from a single piece of suitable high grade spring steel possessing maximum strength, which may be easily applied to the base of 15 a track rail and securely retained in its proper operative position thereon, and which will always effectively grip the rail and cooperate with a stationary part of the road bed to prevent the track rail from creeping. 20 Another object of the invention is to so construct the improved anchor that it will always maintain an intense, effective and rigid engagement with the track rail under all conditions of service.

25 Further objects of this invention are to so construct the anchoring device that it will be corrugated throughout its entire length thus permitting the anchor to be made of comparatively light material and at the same 30 time possessing unusual strength; that it may be removed and reapplied any number of times and always retain its effective tension and gripping power; that it furnishes the required bearing surface against the rail- 35 way tie and extends downwardly into the road ballast, and is so shaped at the point where it extends into the ballast that the vibration and wave motion of the rail will push the ballast apart so that it will not be 40 in constant contact with said ballast thereby preventing interference with the railway electric signaling systems now commonly employed.

The foregoing and such other objects as 45 may appear from the ensuing description are accomplished by the construction, arrangement, location and combination of the several parts hereinafter more fully described, illustrated in the accompanying drawings, and particularly pointed out in the claims appended hereto, it being understood that slight changes in the precise form, proportions and minor details of construction may be resorted to without depart-

ing from the spirit or sacrificing any of the 55 advantages of the invention.

In the accompanying drawings forming a part of this specification it will be seen that:

Figure 1 is a side elevation of the improved device embodying my invention applied to a track rail, showing the track rail in cross-section and in side elevation a railway tie broken away.

Figure 2 is a plan view of the same.

Figure 3 is a plan showing the anchor detached from the track rail, and

Figure 4 is an end elevation thereof.

In the embodiment of my invention as illustrated it will be seen that the numeral 1 designates a railway track rail and 2 an underlying cross-tie forming a stationary part of the road bed and supporting the rail 1, the said rail having a tendency to creep, when subjected to the strain caused by the travel of the rolling stock thereover.

My improved rail anchor 3 is formed from a single piece or bar of high carbon spring steel of the desired or required length provided with a plurality of corrugations throughout its entire length adapted to 80 greatly strengthen the material, having a jaw portion 4 bent upon itself in the manner such as is clearly shown in Fig. 1, the body portion being formed with a downwardly extended portion 5 to provide the desired 85 bearing surface against the railway cross-tie 2, while its outer end terminates with an upwardly extended portion 6, which is adapted to firmly and tightly grip one edge of the rail base and overlap its upper surface as 90 shown in Figs. 1 and 2. The corrugations are formed by hot rolling the material strips or bars, and are more firmly held in their original shape, by having the dies so shaped as to correspond therewith, said corruga- 95 tions being intended to furnish great rigidity, and at the same time to spring outward when the anchor is compressed, or driven on the rail.

It will be seen that the anchor is formed 100 with an off-set portion 7, said off-set beginning at about the inner point of contact with the cross-tie at 8 and terminating at a distance from the cross-tie with the upwardly extended portion 6, thus forming an anchor 105 with its opposite clamping ends off-set from each other, hence when excessive pressure or strain is applied to the depending portion 5,

which is normally in contact with the cross-tie, said pressure will by a shackle action immediately cause the off-set clamping or gripping portion of the anchor at each side of the rail to more intensely tighten its gripping contact with the rail, thus permitting the anchor to be formed of considerably lighter material than that heretofore employed in the construction of anchors possessing the requisite strength.

It will be perceived by reference to Fig. 3 of the drawings, that the corrugations are substantially S-shaped in cross-section which when under pressure will tend to spread, due to the corrugations being thoroughly heat tested, and, hence the corrugations will always naturally tend to spring back to the normal position, thereby imparting a greater pressure and gripping effect against the rail base.

It will be readily obvious that this particular form of rail anchor may be readily driven onto the rail, or may be applied in any suitable or desirable manner.

It is well known that many rail anchors become loose after installation due to corrosion. However, in this type of construction there is always sufficient resiliency to compensate for such corrosion thereby increasing its longevity.

Owing to the particular construction of this anchor, as hereinbefore referred to, it will be evident that the greater the tendency of the track rail to creep, the more intense the gripping action will be imparted to the clamping ends of the anchor, thereby creating a practical and thoroughly effective anti-creeper.

Having thus described my invention what I claim, and desire to secure by Letters Patent is:—

1. A single piece rail anchor comprising a

bar of spring steel corrugated throughout its length and having an off-set clamping member at each end thereof.

45

2. A single piece rail anchor comprising a bar of spring steel corrugated throughout its length, an intermediate depending portion, and an off-set clamping portion at each end thereof.

50

3. A single piece rail anchor comprising a bar of spring steel corrugated throughout its length, a depending portion adapted to contact with a cross-tie, an off-set extending from said depending portion of the opposite end thereof, and an off-set gripping member at each end.

55

4. A single piece rail anchor comprising a bar of spring steel formed with substantially S-shaped corrugations in cross-section throughout its length, a depending portion intermediate its length, an off-set portion extending from the depending portion to one end thereof, and a gripping member formed at each end.

60

5. A single piece rail anchor comprising a bar of spring steel formed with substantially S-shaped corrugations in cross-section throughout its length, a clamping jaw formed at each end off-set from each other, a depending portion intermediate its length, and an off-set portion extending from the depending portion to one end thereof.

65

6. A single piece rail anchor comprising a bar of spring steel formed with corrugations throughout its length, a clamping jaw at each end thereof adapted to overlap the upper surface of the rail base, a downwardly extended portion adapted to contact with a cross-tie, and an off-set portion beginning at the inner end of the downwardly extended portion and terminating at one end thereof.
